United States Patent

Des. 235,092
Patented May 13, 1975

235,092

BOTTLE

Donald J. Leary, Toledo, Ohio, assignor to
Owens-Illinois, Inc., Toledo, Ohio

Filed Aug. 13, 1973, Ser. No. 388,051

Term of patent 14 years

Int. Cl. D9—01

U.S. Cl. D9—149

FIG. 1

FIG. 2

FIG. 3

FIG. 4

FIG. 1 is a front elevational view of a bottle showing my new design;

FIG. 2 is a side elevational view thereof;

FIG. 3 is a top plan view thereof; and

FIG. 4 is a sectional view taken through line 4—4 of FIG. 1.

The sides not shown are the same in appearance as the sides shown.

I claim:

The ornamental design for a bottle, substantially as shown and described.
